UNITED STATES PATENT OFFICE.

JOHANN G. PETERSON, OF HARTFORD, CONNECTICUT.

DESIGN FOR A CAP FOR AN ELECTRICAL ATTACHMENT-PLUG.

56,943.

Specification for Design.

Patented Jan. 18, 1921.

Application filed June 20, 1918. Serial No. 241,087. Term of patent 14 years.

To all whom it may concern:

Be it known that I, JOHANN G. PETERSON, a citizen of the United States, residing at Hartford, in the county of Hartford, State of Connecticut, have invented a new, original, and ornamental Design for a Cap for Electrical Attachment-Plugs, of which the following is a specification, reference being had to the accompanying drawing, forming part hereof.

In said drawings Figure 1 is a front or

face view of the cap, and Fig. 2 is a side elevation of the same showing my new design.

I claim:

The ornamental design for a cap for an electrical attachment plug as shown.

JOHANN G. PETERSON.

Witnessses:

L. L. MARKEL,
HEATH SUTHERLAND.
